UNITED STATES PATENT OFFICE.

SIMON FRIEDBERGER, OF PHILADELPHIA, PENNSYLVANIA.

DESIGN FOR TRIMMING.

SPECIFICATION forming part of Design No. 27,495, dated August 3, 1897.

Application filed February 5, 1897. Serial No. 622,230. Term of patent 7 years.

To all whom it may concern:

Be it known that I, SIMON FRIEDBERGER, a citizen of the United States, residing at Philadelphia, county of Philadelphia, and State 5 of Pennsylvania, have invented a new and Original Design for Trimmings for Fronts of Undervests, Undershirts, Overshirts, and the Like, of which the following is a full, clear, and exact description, reference being had 10 to the accompanying drawings, which form a part of this specification.

My design relates to trimmings for fronts of undervests, undershirts, overshirts, and the like, and has for its characteristic feature 15 an interwoven or ribbed body combined with a border consisting of a looped thread having alternate large and small loops and a straight thread extending through the loops of the other thread.

20 My design is clearly shown in the accompanying drawings; and it consists generally of the body A and border B. The body A is

made of the interweaving of the fine warps *a* with the heavy wefts *a'*, forming a rib-like appearance. The border B is formed of the 25 threads *b* and *c*. Thread *b* is arranged so as to form alternate large loops *b'* and small loops *b''*, the latter extending slightly over the body A. The contiguous warp *a* passes through these loops *b''*. The thread *c* runs 30 straight, interlacing with the loops *b'* of thread *b*.

Having now fully described my improved design, what I claim, and desire to protect by Letters Patent, is—

35

The design for trimmings for fronts of undervests, undershirts, overshirts and the like, substantially as shown.

In testimony of which invention I have hereunto set my hand.

SIMON FRIEDBERGER.
